UNITED STATES PATENT OFFICE

92,624

DESIGN FOR AN ANIMAL FIGURE

Irwin L. Park, Philadelphia, Pa.

Application April 30, 1934, Serial No. 51,590

Term of patent 14 years

To all whom it may concern:

Be it known that I, IRWIN L. PARK, a citizen of the United States, residing at Philadelphia, in the county of Philadelphia and State of Pennsylvania, have invented a new, original, and ornamental Design for an Animal Figure, of which the following is a specification, reference being had to the accompanying drawing, forming part thereof.

Fig. 2 is a side elevation thereof.

The head and back portions of the figure are preferably brown, as indicated by the cross-hatching on the drawing.

I claim:

The ornamental design for an animal figure as shown and described.

In testimony whereof, I have hereunto signed my name.

IRWIN L. PARK.
